UNITED STATES PATENT OFFICE.

MYER DITTEHOFER, OF NEW YORK, N. Y.

SYRINGE.

SPECIFICATION forming part of Letters Patent No. 591,958, dated October 19, 1897.

Application filed March 6, 1896. Serial No. 582,058. (No model.)

To all whom it may concern:

Be it known that I, MYER DITTEHOFER, a citizen of the United States, and a resident of New York, in the county of New York and 5 State of New York, have invented certain new and useful Improvements in Syringes or Syringe-Fittings, of which the following is a specification.

My invention relates to improvements in 10 the manufacture of syringe-nozzles and similar utensils, being applicable, however, to a great many other uses in the arts, indeed, in practically all instances where the presence of a line of severance, such as a slot or opening, would have the effect of cutting out and 15 entirely separating one part of the structure from the other. I will describe my invention, however, as applied to a syringe, because that is a good instance of its use, and one in which 20 I propose to use it.

Until recently, spray-syringes and similar instruments have been made with the nozzle or operative end supplied with a number of perforations, through which jets of the liquid 25 were ejected, but, lately, the so-called "ball-nozzle syringe" has acquired great favor because it delivers a circular, thin sheet of liquid, instead of the series of somewhat contracted jets, and it is believed that the efficiency of the instrument is increased by this 30 construction. The ball-nozzle syringes, however, as well as all others adapted to deliver a sheet of liquid instead of separate jets, known to me, are quite expensive in manufacture, and my present invention, as applied 35 to syringes, relates to improvements whereby the instrument may be constructed at a greatly-reduced cost, and, as I believe, more durably and simply.

Generally stated, my invention consists in thickening or depressing the material of which the syringe is made at its operative end, and on the inside in such manner as that a cutting-tool, which may be used in an ordinary 45 lathe, will make a circular incision or continuous slot in the end of the syringe, entirely through the thickness of the blank, but which will not cut entirely through the depressed or thickened portions. Consequently, they 50 remain as stays or supporting devices for the part which would otherwise be entirely sev-

ered, and the liquid will be ejected through the slit in a fine, thin sheet instead of in jets.

In the drawings hereof, Figure 1 illustrates, partly in section, one form of my invention, in 55 which internal ribs or shoulders are employed. The section is taken on the line 1 1 of Fig. 2. Fig. 2 illustrates a front view of the end of the syringe shown in Fig. 1. Fig. 3 illustrates a view, partly in section, of a syringe having 60 depressed portions. The section is taken on the line 2 2 of Fig. 4. Fig. 4 illustrates a front view of that which is shown in Fig. 3. Fig. 5 illustrates a view, partly in section, of a form of my invention, in which there are 65 two sets of ribs or shoulders and two cuts or incisions in the face of the syringe. The section is taken upon the line 3 3 of Fig. 6. Fig. 6 illustrates a front view of that which is shown in Fig. 5.

I speak of the internal ribs or shoulders and the depressions as being both embraced within my invention. They are so, since they both accomplish the same result, and are, in effect, the same thing, each of them permitting 75 the cutting instrument to make an annular incision deep enough to extend through the material from which the syringe is made from outside to inside, yet not cutting entirely through the depressed ribs or shoulders. Consequently, in both cases, they remain as supports for the part or parts which would otherwise be severed.

A is the body of the syringe. B is the end thereof.

C C C, Figs. 1 and 2, are internal ribs or shoulders which project inwardly and span across the corner between what may be called its "closed end" and the side walls of the syringe.

D is the incision or slot made by the cutting instrument, and E E show where the material of the ribs has not been cut through, on the contrary a portion left to support the part B, which would otherwise be entirely 95 severed and drop away.

In Figs. 3 and 4, A' is the body of the syringe, B' the end thereof, and C' C' C' the depressed portions located in the same relative place as the ribs or shoulders C are in 100 Figs. 1 and 2. D' is the incision. It will be observed that the parts C' C', being depressed

below the line of the cutting-tool, are skipped by it, and remain as supports for the parts B' which would otherwise be severed from the body of the syringe.

5 In Figs. 5 and 6, A² shows the body of the syringe; B², the end thereof. In this case I make two circular incisions or slots, so that there may be two thin sheets of liquid, the inner one bridging the broken spots in the 10 outer one, and vice versa. The ribs are shown at C² C³, and it will be observed that they are in two sets. Those that appertain to the outer incision D² project from about the wall of the syringe inwardly only to the edge 15 of the second incision, whereas the other pair (marked C³) are located between the outer incision D² and the inner one D³. Consequently the outer pair C² C³ support the annular ring between the two incisions, and the pair 20 marked C³ C³ support the interior piece, (marked B²), which would otherwise be severed.

I illustrate three ribs or shoulders in Figs. 1, 2, 3, and 4, because that is a convenient 25 and useful number, but I do not limit myself to them. One such only may be used, or more than three, if desired, and in the forms shown in Figs. 5 and 6 there may be as many of the ribs or shoulders used as desired.

30 I do not limit myself to the details of construction shown and described, since it will be obvious to those who are familiar with this art that modifications may be made therein without departing from the essentials of my 35 invention.

I claim—

1. A syringe-nozzle having a curved slot made in the end thereof, extending entirely through the article, shoulders which are integral with the body of the nozzle, which project inwardly therefrom, and which bridge the slot for supporting the part, which would otherwise be severed, for the purposes set forth. 40

2. A syringe-nozzle having at its end shoulders separated from each other and located on the inside of the end of the nozzle at different distances from the center, and extending below or beyond the plane of the inner surface of the end of the nozzle, whereby a 45 plurality of circular slots may be made which cut through the end of the nozzle, excepting at said separated shoulders, for the purposes set forth.

3. A syringe-nozzle having shoulders located on the inside of the end of the nozzle and separated from each other, and which are integral with the nozzle and extend beyond the plane of its inner surface and which are located at different distances from the 50 center and break joints with each other, for the purposes set forth. 55

Signed at New York, in the county of New York and State of New York, this 13th day of February, A. D. 1896.

MYER DITTENHOEFER.
